Charles S. Gehrie, Montclair, N. J., assignor to
Presto Lock Company, Garfield, N. J., a corpora-
tion of New Jersey

Application April 7, 1954, Serial No. 29,891

Term of patent 14 years

(Cl. D37—2)

To all whom it may concern:

Be it known that I, Charles S. Gehrie, a citizen of the United States, residing at Montclair, in the county of Essex and State of New Jersey, have invented a new, original, and ornamental Design for a Hinge for Luggage Cases, of which the following is a specification, reference being had to the accompanying drawing, forming a part thereof.

In the drawing:

Fig. 1 is a front face view of a hinge for luggage cases, showing my new design;

Fig. 2 is a side edge elevational view of the hinge; and

Fig. 3 is an end elevational view of the same.

I claim:

The ornamental design for a hinge for luggage cases, as shown.
